DESIGN FOR A RACK FOR KITCHEN OR LABORATORY UTENSILS OR THE LIKE

Charles J. Hurschler, New York, N. Y.

Application May 21, 1943, Serial No. 110,248

Term of patent 3½ years

To all whom it may concern:

Be it known that I, Charles J. Hurschler, a citizen of Switzerland, residing in New York city, county of New York and State of New York, have invented a new, original, and ornamental Design for a Rack for Kitchen or Laboratory Utensils or the like, of which the following is a specification, reference being had to the accompanying drawing, forming a part thereof.

Figure 1 is a front elevational view of a rack for kitchen or laboratory utensils or the like, showing my design, with the supporting element in its folded position.

Figure 3 is a perspective view of the article, with the supporting element in another unfolded position.

I claim:

The ornamental design for a rack for kitchen or laboratory utensils or the like, as shown and described.

CHARLES J. HURSCHLER.
